(57) **CLAIM**

The ornamental design for a side-by-side refrigerated display case, as shown and described.

DESCRIPTION

FIG. 1 is a top, front, left perspective view of a side-by-side refrigerated display case according to the design; and, FIG. 2 is a top, front, right perspective view of the side-by-side refrigerated display case shown in FIG. 1 according to the claimed design.

Bottom and back views of the side-by-side refrigerated display case shown in FIG. 1 are not visible during ordinary use of the side-by-side refrigerated display case and thus form no part of the claimed design. Accordingly, no bottom view is disclosed and no back view is disclosed.

In the drawings, the broken lines represent portions of the article which form no part of the claimed design.
